WASHING MACHINE WITH FLUID DRIVE

George P. Castner, Webster City, Iowa, assignor
to Solar Corporation, Milwaukee, Wis., a corporation of Delaware

Application April 12, 1947, Serial No. 741,083

4 Claims. (Cl. 68—23)

1

This invention relates generally to improvements in clothes washing machines of the so-called automatic type wherein the clothes are washed, rinsed and centrifugally wet dried in sequence, and more particularly the present invention relates to improvements in drive or actuating means for the washing and extracting elements of such machines.

The primary object of the invention is to provide improved and novel fluid drive means for transmitting power from the primary power source to the clothes receptacle or spin tub, and optionally to the agitator or washing element all in such manner as to materially improve the operation of these elements and overcome many of the problems well known to the industry in connection with this type of equipment, all as will be hereinafter pointed out.

A further object of this invention is to provide specific improvements in fluid drive units enabling such units to operate with effectiveness on an upright axis with improved results for my purpose and for most convenient belting or driving connection to the proper parts of the washing machine.

These and other important objects of this invention will be made apparent in the course of the following specification wherein reference is had to the accompanying drawing, in which—

Fig. 1 is a vertical sectional view partially in elevation and showing automatic washing machine embodying drive mechanism in accordance with my invention.

Fig. 2 is an enlarged sectional view of the fluid drive mechanism and associated parts alone.

Fig. 3 is a plan view of certain parts of the drive mechanism, showing all the belting between parts.

Fig. 4 is a detail and schematic view somewhat similar to Fig. 2 but showing a modified type of fluid drive arrangement for both the agitator and clothes receptacle.

Fig. 5 is a view similar to Fig. 2 showing drive mechanism like that of Fig. 4, and showing a fluid drive unit in cross section.

Fig. 6 is a view similar to Fig. 2 but showing a fluid drive unit of modified construction.

It may be noted at this point that this application discloses certain improvements over the washing machine disclosed in the co-pending washing machine application No. 690,532, filed August 14, 1946 now Patent No. 2,513,844, issued July 4, 1950, and in which prior application and patent I am a joint inventor. The washing machine, per se, disclosed in Fig. 1 of

2

the accompanying drawings is, in fact, largely identical with that disclosed in the above identified application and will be described herein in only such detail as necessary for the adequate disclosure of my present improvements.

Referring now more particularly to Figs. 1, 2 and 3 of the drawing, the washing machine disclosed therein comprises a stationary housing 10 divided into upper and lower chambers 11 and 12 by a partition plate 13 having at its center an upstanding sleeve 14. The chamber 11 is the washing chamber and is designed to contain water during certain parts of the washing operation as will later appear. The lower chamber 12 is designed to accommodate various operating and driving mechanisms and is closed by a bottom plate 15. This housing structure is supported by adjustable floor jacks designated generally at 16, and resilient pads 17, upon the floor as clearly shown in the drawing.

Positioned within the upper chamber 11 is a clothes receptacle or tub designated generally at 18 which includes an axial center sleeve 19 terminating at its lower end in a conical section

25 20 which is adapted to be secured by cap screws 21 to the top of a tubular spindle 22. This spindle 22 is supported in bearings in a tubular support member 23 which projects upwardly through the aforesaid sleeve 14 from a frame plate 24.

This plate 24 is positioned in the lower chamber 12 and is secured in superimposed relation by connecting posts 25 to a lower plate 26 which in turn is secured to a U-shaped member 27 having a single bearing at its bottom in the base

30 plate of 15 of the housing, as designated at 28. This frame assembly is yieldably held in a centered position upon the bearing by means of a series of radial springs, indicated at 29, stretched between posts 30 upon the upper plate 24 and

35 eye bolts 31 which are attached by means of brackets 32 to adjacent sides of the housing 10. These springs, of course, serve to yieldably center the frame assembly and all parts supported therein in the housing, but since the purpose of

40 45 this mounting, as well as other details thereof are not pertinent to the present invention, they will not be further described herein.

The base portion of the aforesaid conical element 20 has an elliptical sediment trap 33 and secured to the margin of this trap is the lower annular edge 34 of the receptacle wall 35. The wall 35 flares slightly in an upward direction and secured around its upper edge is a balancing ring 36 wherein are formed a series of openings 37 from 50 55 which the water in the tub may be delivered by

centrifugal action when the receptacle is spun, as will later appear. From opposite points on the major axis of the elliptical sediment trap 33 there extend sediment tubes 33 which project upwardly alongside the tub wall 35 and in operation, water and sediment which has settled into the trap are flushed from these tubes 33 at their upper ends by centrifugal action during the spinning of the tub.

Positioned within this tub 18 is an agitator designated generally at 39, which while being of itself of some novelty in construction as pointed out in application No. 690,532, nevertheless operates in more or less conventional manner with an oscillating action to agitate and cleanse the clothes within the tub. So far as material to the present invention, the agitator may be described as having a downwardly flaring or skirted central sleeve 40 which is secured to the upper end of a vertical shaft 41 which extends down through the tubular part 19 of the tub and through the tubular drive spindle 22 therefor. The agitator further, of course, includes radial vanes 42 for agitating the water and clothes.

Water is supplied to the tub 35 for washing and rinsing in any suitable manner, and as here shown through a spray cap 43 which is supported by a pipe 44 over the center of the receptacle and to which the water is led through a supply pipe 45 leading out through one side of the housing 10 as indicated at 46.

At its lower end, the agitator shaft 41 is selectively connectible by means of a conventional jaw clutch 47 to the power output shaft of a conventional transmission unit indicated generally at 48 which is secured beneath the lower frame plate 26. This transmission unit 48 has as its purpose the translation of rotary movement to an oscillating movement and may be of any well known type such as, for example, that shown in Patent No. 1,964,440. The drive shaft 49 for transmission unit 48 is provided with a drive pulley 50 which is operated by a V-belt 51 from an electric motor 52 having a driving pulley 53 on its shaft 54. The motor 52 is hung from the lower frame plate 26 with its shaft 54 extended upwardly through the plate. Also mounted on the motor shaft is a pulley 55 over which runs a V-belt 56 to a pulley 57 on the upper end of the drive shaft for a water pump 58 which is hung from bearing 59 below frame plate 26. The intake of the pump 58 is connected by a hose 60 to a drain outlet 61 in the plate 13 to deliver water from the upper chamber 11 and a discharge pipe 62 from the pump extends out through the side of the machine to deliver the water to a drain or other disposal means (not shown). During certain parts of the washing and rinsing operations, water is quickly discharged from the upper chamber 11 by the pump, preventing the water from reaching the level of the upper end of sleeve 44.

The aforesaid jaw clutch 47 is operated by a bell crank shifter fork 63 actuated by a solenoid 64 and is operated automatically at predetermined times during the washing cycle to complete the driving connection to the agitator 39 causing the transmission unit 48 to oscillate said agitator in a well known manner. The solenoid and shifter fork appear in Fig. 1 but are more clearly shown in Fig. 4.

The tub 18 is rotated or spun by the motor 52 through a fluid drive unit, which is designated generally at 65. In the prior application hereinbefore referred to the fluid drive unit is powered by its own separate motor but I herein use

the same motor 52 for operating both the agitator and tub. To thus support and operate the fluid drive unit, I provide a vertical countershaft 66 which is supported in a bearing 67 and bearing bracket 68 attached to the lower frame plate 26. On this countershaft there is loosely mounted a pulley 69 over which runs a V-belt 70 to a drive pulley 71 (Fig. 1) on the motor shaft 54. A conventional jaw clutch 72 is provided for selectively connecting the pulley 69 to the countershaft and this clutch is opened and closed by a bell crank-shifter fork 73 actuated by a solenoid 74. The fluid drive unit 65 has a pulley 75 which is rotated by the unit and is connected by a V-belt 76 to a large pulley 77 secured on the lower end of the tubular spindle 22 and driving the tub 18.

In the operation of the machine as thus far described the clothes and water are placed in the receptacle or tub 18 and the agitator 39 is set in motion to wash the clothes, at the completion of which operation the agitator is stopped and the tub is rapidly rotated to extract the water. In the latter operation the water and sediment in the trap 33 are flushed out through the tubes 33 and the water is ejected from the receptacle through the openings 37. Rinse water is then admitted and any desired cycle of rinses carried out, with a final rotation of the tub to extract the water, leaving the clothes wet dried at the completion of the operation. The precise cycle of washing and rinsing actions is, of course, immaterial to my present invention.

Various problems, however, arise in the operation of machines of this kind and chief of these with which I am here concerned, are those caused by the effect of the eccentric load represented by the wet clothes in the tub as it is spun. As will be readily appreciated, the clothes are often irregularly disposed about the center of the tub when washing is completed and thus, as the tub is started up to spin the clothes dry, this eccentric or unbalanced load causes a wobbling tendency which sets up a terrific vibration and has many undesirable effects. Then too, the clothes and water in the tub or receptacle represent a very considerable initial load to set in motion with the result that the strain is great and the electrical load, as represented by the current drawn by the motor which spins the tub receptacle, is initially very high. I have found that the use of my fluid drive to the tub absolutely cures both of these undesirable conditions as will now be described in detail.

It will first be understood that the fluid drive unit 65, being of the turbine type, has a vaned impeller or driving rotor and a vaned driven element or rotor, the power transfer between which is accomplished by fluid actuated by the vanes. As best seen in Fig. 2 the unit thus has an outer shell or housing 78 wherein is mounted an impeller rotor 79 having radial vanes 80 operating above corresponding vanes 81 around the lower part of the housing. The construction will be described in more detail hereinafter, along with some novel and advantageous features thereof, but it is sufficient at this point to state that the impeller rotor 79 is driven by the countershaft 66 while the housing 78, which carries the aforesaid pulley 75, is free with respect to the countershaft. The lower part of the housing 78 is filled with fluid to a point such that, when the unit is idle, the fluid will stand just below the level of the lower edges of the impeller vanes 80. To then set the fluid in motion as the impeller starts

to rotate narrow splash or pick-up vanes or paddles 82 are secured to the impeller and depend therefrom down onto the liquid pool, inwardly of the vanes. It will then be understood that as the impeller starts up these vanes 82 will pick up and set the body of fluid in motion so that it will travel outwardly and climb or vortex until the impeller vanes 80 obtain a bite on the fluid and complete the fluid driving connection between impeller and driven elements.

It will now be evident that by virtue of the initial high slippage factor, which occurs as the fluid drive unit is first started up and as the fluid is being set in motion, the load represented by the tub or receptacle 18 and contained clothes and water will be quite gradually applied to the motor 52. As a result I completely eliminate or at the least greatly reduce the high starting electrical load, which is common to other machines using mechanical clutches and the like between motor and receptacle or spin tub, and which load sometimes requires special wiring for the machine and at best causes frequent fuse burnouts. For example, and from actual tests with a ten ampere ammeter in the load circuit to the motor, in my machine the starting load as the spinning operation begins may run at about three amperes, whereas in another machine of well known make, the corresponding starting load will cause the ammeter needle to fly completely off scale. The importance of this feature of my machine, achieved through use of the fluid drive for the receptacle, can well be appreciated.

This "cushioned" electrical load has the further, very desirable feature of permitting the starting switch of the motor to throw out immediately so that the motor starts off at practically full speed. In other machines to my knowledge using mechanical clutching, or even if such machines used a fluid clutch without my high slippage factor, the load builds up so rapidly that the starting switch sometimes fails to throw out and the motor sometimes burns out.

Also of great importance to the successful operation of the machine is the "automatic" accommodation of the fluid drive to varying eccentric loads and the regulation of the tub or receptacle speed according to load conditions. In this connection it will be noted that the impeller and driven vanes 80 and 81 are comparatively short radially, as compared to the usual fluid drive or clutch, and that the fluid drive unit is but partially filled with fluid. These characteristics, plus the obvious tendency of the fluid to settle as the unit slows down, due to its being mounted upon a vertical axis, all contribute to determine the normal slippage factor of the drive unit. Thus, there is an initial slippage, even with no load on the unit, which is substantially and desiredly greater than present in the usual fluid coupling, used in the usual way. And as the load increases a proportional increase in slippage results. It follows then that, if the clothes are eccentrically disposed about the axis of the tub or receptacle as it is set in motion, slippage of a magnitude dependent on such eccentric load will occur in the fluid drive and the receptacle will run comparatively slow until the unbalanced load condition corrects itself, which it tends to do as the spinning proceeds and the water is centrifuged from the clothes.

It will now be evident that since the speed of the tub or receptacle 18 is proportional to the eccentric load, the vibration will be very greatly reduced to thus overcome one of the chief prob-

lems in this type of machine and it will be further understood that if the machine is started up with a considerable eccentric load, its comparatively low speed under that load will increase gradually as the magnitude of the load itself decreases. In other words, as the water is expelled from the clothes, the eccentric load represented by the wet clothes will gradually decrease and the rotating speed of the tub will 10 pick up so that the final extraction speed will be high enough to insure complete extraction. In other machines with which I am familiar, it is necessary to set a maximum speed limit for the tub which is low enough to permit operation 15 under the worst expected eccentric load conditions and as a result the extraction time is increased unnecessarily. In such a machine the receptacle speed is ordinarily in the vicinity of 500 to 575 R. P. M. so that the vibration will not be excessive with the greatest expected load unbalance and it will be readily appreciated that this places a definite limitation upon the completeness and speed of the extraction process.

The initial high slippage factor of the fluid drive unit and resulting gradual acceleration of the tub speed also has operational advantages other than cushioning the electrical load. The chief advantage lies in the action of the clothes at the start of the extraction process which may be described as follows: When the machine has reached the time in its operation for extraction of the water, the clothes are, of course, floating about upon and in the water and now as the tub is set in motion the slow acceleration will cause the water and clothes to vortex but before there is any pronounced tendency for the clothes to climb upward toward the rim of the receptacle, they will have settled outwardly and downwardly into a mass as indicated in Fig. 1 around the receptacle wall. As the water then proceeds to spill upwardly and outwardly from the receptacle through the openings 37 it will carry along its surface accumulation of suds and similar materials and will expel such materials before it has 35 a chance to settle upon the clothes. This action, of course, leaves the clothes much cleaner and in practice is found to be a considerable advantage. It will also be understood that the gradual acceleration of the tub speed will allow the sediment to remain trapped in the sediment trap 40 45 50 55 33 without any tendency to flush out with the water and into the clothes with the result that this sediment is delivered through the tubes 38 without any possibility of coming in contact with the clean clothes.

Referring now more particularly to Fig. 2 of the drawing, it will be seen that the impeller unit or rotor 79 of the fluid drive unit is formed with a mounting sleeve 83 which is threaded at 84 upon the countershaft 66 in order to anchor the fluid drive unit upon the shaft. The housing 78 is composed of half sections 85 and 86 which, when the assembly of the unit is completed, are welded together around their edges 60 65 at 87 and the housing further has a mounting sleeve 88 which is rotatably mounted upon bushings 89 around the aforesaid sleeve 83. Thus, the housing 78 is mounted to rotate entirely independently of the impeller rotor and countershaft. The impeller 79 is further locked upon the countershaft by a diametrical key 90 which stands in spaced relation to a removable plug 91 which is screwed in the center of the top of the housing 78. This plug is primarily for the 70 75 purpose of filling the unit with fluid as will be

apparent. For the best operation of the fluid drive unit for my purpose, I find that the fit of the housing upon the bushings 89 should not be too tight so that no binding will result which would interfere with the proper utilization of the high slippage factor of the unit. This is particularly true since as the unit operates it has some tendency to heat and the resulting expansion would so increase the binding effect as to cause a gradual reduction in the speed of the tub. I, therefore, so machine the parts that sufficient play is present to prevent this undesirable result but this in turn brings about a tendency toward end play of the parts causing a chattering noise to be set up while the unit is running. To overcome this, I provide a resilient automatic end play take-up which is here shown in the form of a ball 92 which bears in a recess in the aforesaid lock key 90 and is pressed yieldably thereagainst by a spring 93 placed in the plug 91 and bearing upon the ball. This device then operates to urge the housing 18 upwardly with respect to the impeller 79 and automatically take up end play as it occurs and I have found that it completely overcomes this chattering problem.

It is, of course, possible to utilize the fluid drive unit 65 to drive not only the tub or receptacle but also the agitator 39 and I show, for example, a drive mechanism set up for this purpose in Figs. 4 and 5. Such drive arrangement may, in fact, be found to be preferable to direct mechanical drive of the agitator since I am thus enabled to use the slippage factor of the fluid drive unit to cushion the end of the agitator strokes with the result of further reducing vibration and wear and tear upon the parts, as will be understood. Referring now to Fig. 4 I show an electric motor 94 which is supported by a bracket 95 upon a lower plate 26 with the motor shaft 96 extended upwardly. In this case the fluid drive unit 65, which may be identical to that just described, is mounted upon the upper end of the motor shaft 96 and is directly driven thereby. The pulley 75 upon the fluid drive unit operates the large pulley 77 for driving the receptacle 18 by means of a belt 76 exactly as previously described and in addition I mount another pulley 97 by means of screws 98a upon the lower face of the pulley 75 and over this run a V-belt 98 to the drive pulley 50 for the transmission unit 48. As best seen in Fig. 5 the pulley 97 clears the motor shaft 96 and thus it will be evident that the transmission unit 48 is powered only through the fluid drive unit 65. The drive for the water pump 58, which does not appear in Fig. 4, may be taken from a pulley 99 upon the drive shaft 49 of the transmission unit or directly off the motor shaft as may be desired.

It will thus be seen that since the fluid drive unit operates both the agitator and the tub or receptacle the cushioning effect will be applied to both with a further material reduction in vibration. In order, however, to take advantage of the high initial slippage factor of the fluid drive unit for gradually accelerating the tub, it is now necessary to start and stop the motor 94. Thus, at the completion of the washing cycle the motor will be stopped and then started up again to carry out the extraction cycle and bring about the initial high slippage in the fluid drive unit as is desired for my purpose. It is further necessary to provide a conventional jaw clutch as indicated at 100 for selectively establishing

the drive connection between the pulley 77 and tubular drive shaft 22 for the tub 18 so that the tub may be disconnected from the fluid drive unit except during the extraction process. The clutch 100 is actuated by a bell crank lever and shifter fork indicated at 101 which is in turn operated by a solenoid 102. The clutch 47 for controlling the operation of the agitator as previously described is also used and I have indicated diagrammatically an electric circuit for controlling the motor 94 and the respective clutch actuating solenoids 64 and 102. This circuit will, of course, vary with the type of automatic timing switch used in the machine and as here shown the switch is of the commutator type operated by a switch motor 103 and with separate switch segments 104, 105 and 106 for controlling a circuit from one side of the power line 107 to conductors 108, 109 and 110 leading respectively to the motor 94 and solenoids 64 and 102. The remaining side 111 of the line is connected as shown directly to these elements to complete the circuit. By proper arrangement of the switch segments it will be possible to start and stop the motor and actuate the solenoids in any desired sequence to control the action of the agitator and of the tub and to stop the motor before the clutch 100 is engaged so that the gradual acceleration of the tub will take place. Since the electrical circuit of itself forms no part of my present invention, it will not be described in further detail herein.

Referring to Fig. 5 I show a fluid drive unit 65 which embodies a slight modification over that of Fig. 2. However, the construction is basically the same and corresponding parts throughout are given the previously used reference numerals. In this drive unit of Fig. 5, however, the splash vanes 82 are not used and instead I run the fluid level at least, as indicated at 112, slightly above the lower edges of the impeller vanes 80. Thus, it will be seen that when the unit is set in operation these impeller vanes will have a limited bite in the fluid sufficient to set it in motion to establish and complete the driving connection between the vanes. To then introduce the necessary high slippage factor in the drive unit, I considerably shorten the impeller vanes 80 and driven vanes 81, in comparison to the corresponding vanes in the drive unit of Fig. 2, and find that by so shortening the vanes, and by selection of a fluid of proper viscosity I am able to obtain the desired slippage factor previously described.

I further show another modification of the drive unit in Fig. 6 and here again the corresponding parts are given the similar reference numerals. In this case, however, the impeller vanes 80 angle inwardly and downwardly at their lower edges while the driven unit vanes 81 are reduced in height and angle in the same direction as clearly shown. Thus, I form acute corner portions 113 at the inner ends of the impeller ends 80 which may dip into the fluid pool when the unit is at rest and which will then serve to set the fluid in motion when the unit is started up. Here again, I find that proper selection of the fluid type and level and angle of the respective vanes enables me to obtain the desired slippage in the drive unit.

It is understood that suitable modifications may be made in the structure as disclosed, provided such modifications come within the spirit and scope of the appended claims. Having now

therefore fully illustrated and described my in-

vention, what I claim to be new and desire to protect by Letters Patent is:

1. For a clothes washing machine having a rotary clothes receptacle and a motor for rotating the receptacle, a fluid coupling comprising upper and lower fluid coupling elements operatively supported for rotation about a generally upright axis and connected, respectively, to the motor and receptacle, the upper coupling element having an annular series of depending vanes and the lower element having a similar series of vanes in opposed positions with respect to the vanes of the upper coupling element, means supporting a fixed charge of fluid in cooperative relationship with the coupling elements for establishing a variable slip fluid drive connection between the motor and receptacle, the said fixed charge of fluid being such that it will stand at a level below the major areas of the vanes in the upper coupling element when the coupling elements are at rest but these vanes having lower portions of comparatively minor areas depending into the fluid for engaging and gradually actuating the fluid into full transmission contact with the vanes.

2. For a clothes washing machine having a rotary clothes receptacle and a motor for rotating the receptacle, a fluid coupling comprising upper and lower fluid coupling elements operatively supported for rotation about a generally upright axis and connected, respectively, to the motor and receptacle, the upper coupling element having an annular series of depending vanes and the lower element having a similar series of vanes in opposed positions with respect to the vanes of the upper coupling element, means supporting a fixed charge of fluid in cooperative relationship with the coupling elements for establishing a variable slip fluid drive connection between the motor and receptacle, the said fixed charge of fluid being such that it will stand at substantially the level of the vanes of the lower coupling element when the coupling elements are at rest, and the vanes on the upper coupling element having corner portions dipping into the fluid at rest and thereby engaging the fluid to gradually actuate it into transmission contact with the vanes of the upper coupling element.

3. For use in a washing machine, a first mem-

ber to be oscillated and a transmission device connected thereto and of the type converting rotary motion to oscillating motion, a second member to be rotated, a fluid coupling having cooperating vaned driving and driven elements and means forming a sealed chamber thereabout containing fluid in an amount less than the total capacity of the chamber whereby slippage will accompany the transmission of torque through the coupling, an electric motor and means operatively connecting the same to the driving element, and separate selectively operative means connecting the driven element respectively to the first member through the transmission device and to the second member.

4. For use in a washing machine, a first member to be oscillated and a transmission device connected thereto and of the type converting rotary motion to oscillating motion, a second member to be rotated, a fluid coupling having driving and driven elements and of a type characterized by having a high initial slippage factor, an electric motor, means connecting the motor to the driving element of the fluid coupling, and separate clutches operatively arranged to selectively connect the driven element of the coupling to the transmission device to oscillate the first member and to the second member to rotate the same.

GEORGE P. CASTNER.
